UNITED STATES PATENT OFFICE.

MILLARD F. McCRAY, OF COWGILL, MISSOURI.

SHOCK-BINDER.

1,259,647.

Specification of Letters Patent. Patented Mar. 19, 1918.

Application filed April 28, 1915. Serial No. 24,566.

To all whom it may concern:

Be it known that I, MILLARD F. McCRAY, a citizen of the United States, residing at Cowgill, in the county of Caldwell and State 5 of Missouri, have invented certain new and useful Improvements in Shock-Binders, of which the following is a specification.

My invention relates to cord and rope 10 holders, and more particularly to a new and improved shock binder.

The primary object of my invention is to provide an improved shock binder which is simple in construction, cheap to manufacture, strong, durable, and one which is 15 quickly and easily disposed in position for binding a shock of corn or the like.

Another object of my invention is to provide improved means associated with my shock binder for guiding the binding element, as well as means for facilitating the 20 tightening of the binding element and the fastening of the same in tightened position.

A further object of my invention is to provide a shock binder of the class above described having means thereon for engagement with a shock adapted to embrace the latter, and means for facilitating the tightening of said engaging means.

With the above and other objects in view 30 my invention resides preferably in the construction, combination, and arrangement of parts as hereinafter set forth in the specification and illustrated in the accompanying drawings, in which—

Figure 1 is a perspective view of my improved shock binder.

Fig. 2 is a longitudinal sectional view of the same.

Similar reference characters indicate similar parts throughout the various views of the drawings.

Referring more particularly to the drawings in which the preferred embodiment of my invention is illustrated, I provide a 45 frame designated generally by the numeral 1, said frame comprising a pair of strips 2 and 3 having portions 2' and 3', said strips being riveted or otherwise secured together as indicated at 4, and a transverse bar 5 associated therewith adjacent the point at which said strips 2 and 3 are secured. The extremities of the transverse bar 5 are angularly bent as indicated at 6 for a purpose 50 which will hereinafter appear.

55 The opposite extremities of the strips 2 and 3 are in spaced relation, the strip 3 be-

ing offset as at 7 and disposed in spaced relation to the strip 2 forming the spaced parallel portions 2' and 3' hereinbefore referred to, the free extremities of the strips 2 and 3 being flared outwardly as indicated at 8 and 9 for a purpose which will herein-after appear, the strip 2 being extended beyond the strip 3 and provided with an aperture 10 through which a flexible band, rope 60 or the like 11 is received, a knot 12 being formed on the adjacent extremity of the rope 11 to prevent its passage entirely through the aperture 10.

A sheave 13 is mounted on a transverse 70 pin 14 having a nut 15 and a head 16 to prevent its dislodgment from the strips 2 and 3, said sheave 13 being preferably disposed between the spaced portions of the strips 2 and 3.

In use the rope 11 is disposed about a shock or the like, the free extremity 17 thereof being trained over the transverse bar 5 as shown at 18 and further disposed over the sheave as indicated at 19, the free extremity 17 thereof being received in the spaced diverging extremities 20 and 21 of the strips 2 and 3, respectively, and frictionally retained therein owing to the inherent resiliency of the metal employed, the 80 diverging portions 20 and 21 forming a wedge slot 22.

It will be noted that the tightening of the band or rope 11 on a shock or the like is facilitated by the provision of the sheave 13, 90 and it will also be noted that the direction of pull exerted on the binding element is such that it tends to draw the rope or band 11 taut. This allows of the tightening of the device without holding the same in position, it only being necessary to support the device until the rope is trained over the sheave 13, whereupon exertion of force on the free extremity of the rope 11 will cause the same to tighten about the shock. The 100 transverse bar 5 has been provided to afford an abutment and guide over which the rope 11 may be disposed, and should it be desired, anti-friction means may be placed at the point designated 18. However, it is not 105 absolutely necessary, as I have found in actual use of the device, that the slight amount of friction involved at this point is negligible. It is, of course, to be understood that the advantage of the abutment 5, preferably 110 rounded, is to prevent tearing or marring of the binding element. Attention is called

to the fact that the device may be used left or right handed, the bar 5 extending to substantially equal lengths beyond either marginal edge of the frame. The down-turned 5 extremities 6 of the transverse bar 5 serve to prevent dislodgment of the binding element therefrom during the binding operation.

When the object being bound is clamped 10 sufficiently the rope or binding element is engaged in the wedge slot 22 as shown to advantage in Fig. 1 thereby preventing loosening or disengaging of the binder.

It is to be understood, of course, that the 15 frame as well as the transverse bar 5 may be cast in one piece, however, I prefer to form the same in the manner shown, since this construction, not only affords means for supporting the sheave 13 but also provides the spaced arms 20 and 21 for clamping. In actual practice it may be found 20 desirable to stamp the transverse bar 5 and the strip 2 in one piece and this is a structure which would be desirable when reducing the invention to practice.

Having thus described my invention, what I claim and desire to secure by Letters Patent is;

1. A shock binder, including a frame 30 formed into a gripping jaw at one end, a flexible binding element secured to the other end of the frame and adapted to be received by the jaw, an anti-friction element adapted to receive the binding element, and a guiding abutment for the flexible element disposed transversely of the frame.

2. A shock binder, comprising a frame including spaced parallel portions, a sheave disposed between the parallel portions, a 40 clamping jaw formed by the opposite extremities of said frame, a flexible binding element, and a transversely disposed bar positioned upon said frame providing guide and abutment for the flexible element.

45 3. A shock binder, comprising a frame including spaced parallel portions, said frame terminating in a resilient jaw, a transverse guiding abutment secured to the frame be-

tween the jaw and the parallel portions, a 50 guide sheave rotatably mounted between the parallel portions, and a flexible binding element secured to one of the parallel portions.

4. A shock binder, comprising a frame consisting of a main strip having an oppositely curved end, a second strip secured 55 thereto having a curved end coinciding with the curved end of the main strip to form a resilient jaw, the remaining portion of said second strip being off-set to extend parallel with said main strip to form straight parallel portions; a sheave rotatably mounted between said parallel portions, a guiding abutment secured in transverse relationship to the frame, and a flexible binding element secured to the main frame member adapted 60 to be looped over the guiding abutment, the sheave and between the curved members of the jaw.

5. A shock binder, comprising a frame, 70 said frame being formed of a pair of strips, one strip being off-set and extending substantially parallel with the remaining strip, a sheave rotatably mounted between said parallel portions, the remaining end portions of said strip being curved to one side, 75 to form a resilient gripping jaw, said resilient gripping jaw being substantially in alignment with said sheave, a transverse bar secured to said strip and having angularly bent ends projecting to overhang said strips, 80 whereby the sheave, resilient jaw and ends of said bar will extend so as to be free from the shock into engagement with which the device is positioned, thus preventing the device from being entangled in a shock, and a 85 flexible binding element secured to said frame and being looped around said transverse bar and over said sheave and between said resilient jaw.

In testimony whereof I affix my signature 90 in presence of two witnesses.

MILLARD F. McCRAY.
